PREPARATION OF VITAMIN A PALMITATE

George Y. Brokaw, Rochester, N.Y., assignor to Eastman Kodak Company, Rochester, N.Y., a corporation of New Jersey

No Drawing. Application October 31, 1955
Serial No. 544,069

1 Claim. (Cl. 260—410)

This invention relates to the preparation of vitamin A esters, and more particularly, to a process for preparing higher fatty acid esters of vitamin A.

Vitamin A is a highly unsaturated compound that is too unstable to esterify directly with higher fatty acids without substantial destruction or reduction of its vitamin A biological activity. Thus, the usual method used for preparing higher fatty acid esters of vitamin A is to esterify with higher acyl halides in the presence of such substances as pyridine, the pyridine being difficult to separate from the final product. Further, such higher acyl halides as palmitoyl chloride require special procedures and techniques because of their highly corrosive nature and their instability in the presence of even small amounts of water. Accordingly, it is desirable to have a more convenient means for preparing higher fatty acid esters of vitamin A.

It is thus an object of this invention to prepare higher fatty acid esters of vitamin A by a new and improved process.

It is another object of this invention to prepare vitamin A palmitate from vitamin A by novel means.

It is a further object of this invention to prepare higher fatty acid esters of vitamin A having good color and stability by a new method.

These and other objects are accomplished by interesterifying vitamin A with higher fatty acid esters of lower alkyl monohydric alcohols in the presence of a basic interesterification catalyst.

The vitamin A esterified by the present process can be prepared by chemical synthesis, or it can be prepared from natural sources such as from fish liver oils.

The higher fatty acid esters of lower alkyl monohydric alcohols used in the present process comprise a wide range of ester materials. Any ester of a lower alkyl monohydric alcohol having from 1 to 6 carbon atoms, and which is esterified with a higher fatty acid having more than 6, and preferably less than 22 carbon atoms, can be utilized. Esters containing fat-forming fatty acid radicals are preferably employed. Typical of the higher fatty acid esters of lower alkyl monohydric alcohols that can be suitably used are methyl palmitate, ethyl palmitate, butyl stearate, methyl oleate, propyl linoleate, methyl myristate, methyl laurate, and the like. Likewise, mixtures of several higher fatty acid esters of lower alkyl monohydric alcohols, such as methyl esters of fat-forming fatty acids derived from vegetable oils or animal fats, can also be utilized.

Any of the well-known basic interesterification catalysts can be used in the present interesterification process. The alkali metal lower aliphatic alcoholates containing from 1 to 6 carbon atoms are particularly effective, and include such compounds as sodium methoxide, potassium ethoxide, lithium isopropoxide and related alcoholates. Such alcoholate catalysts are preferred as they are effective at relatively low temperatures, usually temperatures of about 40°—90° C. being employed with such catalysts, although some alcoholate catalysts are ef-

2

fective at about room temperature. Likewise, related alkaline earth metal lower aliphatic alcoholates can be used, and include such compounds as calcium methoxide, barium isopropoxide, magnesium ethoxide, and the like. 5 Also, alkali metal and alkaline earth metal hydrides and amides such as sodium hydride, potassium amide can be used. However, basic interesterification catalysts that are effective at higher temperatures, such as at temperatures higher than about 175° C., can also be employed. Suitable high temperature interesterification catalysts include alkali metal or alkaline earth metal soaps and hydroxides or oxides, such as, sodium palmitate, lithium palmitate, barium hydroxide and the like. Only relatively small proportionate amounts of the present catalysts need be 10 employed to effect the present interesterification reaction, the amount of catalyst necessary varying mainly with the type of catalyst and the nature of the reaction composition. Typical catalytic amounts of sodium methoxide, for example, are about .2%—5% by weight of the reaction 15 composition, larger amounts of sodium methoxide likewise being satisfactory.

In carrying out the invention, the vitamin A is combined with the higher fatty acid ester of a lower alkyl monohydric alcohol in the presence of a catalytic amount 20 of a basic interesterification catalyst and the mixture reacted until the resulting interesterification is substantially complete. The temperature of the reaction can be widely varied, the temperature depending primarily on the type of catalyst employed. If the higher fatty acid ester of a lower alkyl monohydric alcohol is solid at room temperature, this ester is usually melted prior to being incorporated into the reaction mixture. Likewise, the reaction 25 can be effected in an inert organic solvent media, such solvents as xylene, toluene, benzene, petroleum ether, diethyl ether being suitably employed. Usually a stoichiometric excess of the higher fatty acid ester of a lower alkyl monohydric alcohol is employed, although the present interesterification reaction can be effected with stoichiometric proportions of the reactants. The reaction 30 can be effected under vacuum and the lower alkyl monohydric alcohol resulting from the interesterification reaction removed during the course of the reaction. The reaction time typically varies from about 1 hour to 2 or 3 hours, or even longer, the reaction time depending on 35 such variants as the catalyst, the reaction temperature, the reactants themselves, and other related variants. The reaction mixture is preferably stirred or agitated to increase the effectiveness of the catalyst. After the reaction is completed, the inert organic solvent, unreacted 40 higher fatty acid ester of a lower alkyl monohydric alcohol, and lower alkyl monohydric alcohol resulting from the interesterification reaction can be readily separated from the vitamin A ester product by vacuum distillation. Likewise, the prepared higher fatty acid ester of vitamin 45 A can be separated from the interesterification reaction mixture by any of the other well-known separating means, such as by chromatographic adsorption, for example.

The invention is illustrated by the following example of a preferred embodiment thereof, it being understood 50 that the example is illustrative only and not intended to limit the scope of the invention unless otherwise specifically indicated.

Example

To a 120.40 g. sample of vitamin A prepared by chemical synthesis and having

$$E_{1\text{ cm}}^{1\%} (325) = 1628$$

was added 180.6 g. of melted methyl palmitate and 1.5 g. of sodium methoxide. The resulting mixture was thereafter reacted at a temperature of about 60° C. for 60 minutes at a reduced pressure with constant stirring. The resulting reaction mixture was thereafter cooled with

600 ml. of petroleum ether (boiling range 60°-100° C.) containing a small amount of Dry Ice. The cooled reaction mixture was filtered and the resulting filtrate was vacuum distilled to give 296.4 g. of vitamin A palmitate having

$$E^{\text{1}}_{\text{cm}}(326) = 655$$

for a yield of about 99%. (The yield was calculated from ultra-violet absorption data.) Similarly, other higher fatty acid esters of a lower alkyl monohydric alcohol can be interesterified with vitamin A to produce higher fatty acid esters of vitamin A. Higher fatty acid esters of vitamin A prepared in accordance with the present process are particularly characterized as having good color and stability.

Thus, by means of this invention, higher fatty acid esters of vitamin A can be readily and conveniently prepared.

Although the invention has been described in detail with particular reference to certain preferred embodiments thereof, it will be understood that variations and

modifications can be effected within the spirit and scope of the invention as described hereinabove and as defined in the appended claim.

I claim:

5 The method of preparing vitamin A palmitate having improved stability to oxidative deterioration which comprises subjecting vitamin A alcohol and methyl palmitate to an alcoholysis reaction in the presence of a catalytic amount of sodium methoxide and thereby forming vitamin A palmitate.
